UNITED STATES PATENT OFFICE

GEORGES SUDEE, OF PANTIN, FRANCE

SWITCH

Application filed January 5, 1931, Serial No. 506,825, and in France February 22, 1930.

In motor vehicles which are provided with a storage battery, it is of great advantage to be able to break the circuit of the battery when the engine stops, in a reliable manner, so as to avoid all loss of current or risk of fire. More particularly, in vehicles provided with what is known as the "Delco" ignition system, it is quite necessary to break the circuit when stopping, or otherwise the battery will run down, and the induction coil may also be damaged while the vehicle is at rest.

The present invention relates to an automatic device for breaking the circuit when the engine stops, and comprises a piston which will rise in a cylinder by the engine suction, thereby closing the circuit, and when the engine stops, the piston will fall by its own weight to open the circuit.

The said apparatus is essentially characterized by the combination of a closed cylinder which is connected by a conduit with the suction pipe of the engine, and whose end consists of a flexible diaphragm (of the aneroid or other type) which allows no leakage of gas or vapours; also by the use of a second chamber serving as a damping chamber which is interposed in the conduit which connects the cylinder with the suction pipe of the engine and whose inlet and outlet orifices have a relatively small cross section adapted to impede the flow of the withdrawn fluid; and further, by the use of a piston movable in said cylinder, and of electric contact-pieces which are mounted in an elastic manner and which are placed in contact by a suitable driving member mounted on the piston.

The accompanying drawing shows by way of example two embodiments of the invention.

Fig. 1 shows a circuit-breaking device in vertical section.

Fig. 2 is a similar view of a modification of said device.

Fig. 3 is a section on a larger scale of the suction conduit of the apparatus.

Fig. 4 is a sectional view of the suction conduit of the carburettor, showing an additional register by which the functioning of the apparatus is assured.

As shown in Fig. 1, the cylinder 1 is connected by a conduit 8 with the suction pipe of the engine, and the conduit including an expansion chamber 11, whose inlet and outlet orifices 12—13 are calibrated. The chamber 11 might be eliminated, by making the said conduit 8 large enough to answer the same purpose.

In the cylinder 1 is mounted a light piston 4 which preferably comprises only the grooves 14, and without piston rings, this arrangement being sufficient to afford leakless conditions. Said piston 4 carries at the top a contact-piece 5. It is also preferable to maintain the relatively reduced space between the piston and the upper end 2 of the cylinder.

The upper contact-piece 6 is connected to an insulated terminal 15 by a spring strip 16.

The lower end of the cylinder 1 is closed by a flexible diaphragm 17 (an aneroid diaphragm or the like) which will curve inwardly when the piston 4 rises, and thus introduction of dust into the cylinder is prevented. The said diaphragm, which is more or less fragile, is preferably supported by a wire-gauze member 18, or by suitable stiffening means, and it is provided with an orifice of determined section.

At the end of the said conduit 8, there is preferably mounted in the engine suction pipe 10 a nozzle 8a which diverges in the direction of fluid flow.

In the modification shown in Figs. 2 and 3, the apparatus comprises two insulated terminals 15—19 to which the ends of the circuit wires are connected.

The terminal 15 is connected by a spring strip 16 with a contact-piece 6, whilst the terminal 19 is connected by a strip 21 with a contact-piece 20. The piston 4 carries a

stop 5 of insulating material which is adapted to move the contact-piece 6 against the contact-piece 20 to close the circuit.

The stroke of the piston is limited by an insulating stop 23 mounted on the end of the cylinder beyond the contact-piece 20.

The diaphragm 17 consists preferably of leather, and comprises concentric corrugations as well as a flanged edge, after the manner of pressed leather disks. The diaphragm is supported by a piece of wire 24 in the form of a ring. Said diaphragm rests at its periphery upon a washer 25, mounted on a shoulder of the main body 1 of the apparatus; the inner edge of said washer is rounded off or faced with a round member at its lower part, in order to form a seating for the diaphragm.

The piston 4 is of hollow form, and on its convex bottom are formed one or more circular ribs 26 corresponding to the concave portions of the diaphragm, whereby the directions of curvature of said diaphragm will be preserved even under a strong pressure, thus avoiding damage. The orifice through which the suction is effected in the main body 1 is normally closed by a disk 27 which rises when the engine is operating and cooperates with its seat by gravity. Said disk prevents all improper admission of air into the apparatus in the case of back-fire in the carburettor, and delays all such admission when the vacuum becomes very small, for instance after a sudden increase of engine speed, and the contact is thus maintained until the next action of the vacuum. In order that the said disk 27 may descend when the engine stops it is pierced with a very small hole 28.

Fig. 4 shows a device adapted for motors which are started by a strong injection of liquid fuel, and which must therefore start with the gas throttle fully open. The device comprises an additional register or valve adapted to close the suction pipe when the engine is out of action, thus producing in the apparatus a sufficient vacuum to close the circuit at the contacts when starting, and the said valve then moves aside under the effect of the suction.

10 is the suction conduit of the engine, and 29 the gas throttle, above which is a register or disk valve 30 pivoted on a concentric axle 31, said valve being normally held stationary in the horizontal position by a stop 32 and 55 also from the fact that its portion opposite the said stop is relatively heavier. Thus when the engine is started, the small vacuum thus produced will be sufficient to operate the electric contact, since the valve 30 is now 60 closed, and when the engine runs normally, said valve pivots about into the vertical position and offers no obstruction to normal operation.

In order to reduce the volume of said valve 30, which might obstruct the flow of gas, an

external lever may be provided which is secured to the axle and serves as a counter-weight, so that the valve will close automatically, and thus the thickness of said valve may be reduced to the minimum.

I claim:

1. A circuit-breaking device including a cylinder having a lower open end, a piston operative in the cylinder comprising a hollow body having an upstanding central stem, 75 electrical contacts carried by the cylinder and directly operated in one direction by the stem of the piston, and a diaphragm closing the open end of the cylinder below the piston, said diaphragm responding to piston movements while maintaining a seal at the lower end of the cylinder.

2. A circuit-breaking device including a cylinder having a lower open end, a piston operative in the cylinder comprising a hollow body having an upstanding central stem, 85 electrical contacts carried by the cylinder and directly operated in one direction by the stem of the piston, and a diaphragm closing the open end of the cylinder below the piston, said diaphragm responding to piston movements while maintaining a seal at the lower end of the cylinder, the lower end of the piston being convex and formed with a 90 circular rib and the diaphragm being formed with concave portions in correspondence with said circular rib.

3. A circuit breaking device including a cylinder, the lower end of which is open, a piston working in the cylinder and constituted by a hollow body in the shape of a shield, with a central rod directed upward, electric contacts mounted upon the cylinder and actuated directly in the one direction by the piston rod, and a diaphragm closing the 105 extreme open end of the cylinder underneath the piston, said diaphragm leaning upon a ring placed against a shoulder of the cylinder and accompanying the movements of the piston by maintaining tight the lower 110 end of the cylinder.

4. A circuit breaking device including a cylinder, the lower end of which is open, a piston working in the cylinder and constituted by a hollow body in the shape of a 115 shield, with a central rod directed upward, electric contacts mounted upon the cylinder and actuated directly in the one direction by the piston rod, a diaphragm closing the extreme open end of the cylinder beneath the 120 piston, said diaphragm accompanying the movement of the piston by maintaining tight the extreme lower end of the cylinder, and the extreme upper end of the cylinder connecting with a small opening and a buffer 125 chamber joined by second small opening to suction tube.

5. A circuit breaking device including a cylinder, the lower end of which is open, a piston working in the cylinder and constitut- 130

ed by a hollow body in the shape of a shield,
with a central rod directed upward, electric
contacts mounted upon the cylinder and ac-
tuated directly in the one direction by the
5 piston rod, a diaphragm closing the extreme
open end of the cylinder beneath the piston,
and the upper extreme end of the cylinder
being joined to suction tube by a nipple in
which a disk valve is arranged pierced by a
10 small opening.

In testimony whereof I affix my signature.
GEORGES SUDER.
